UNITED STATES PATENT OFFICE.

BINA M. WEST, OF PORT HURON, MICHIGAN, ASSIGNOR TO THE SUPREME
HIVE LADIES OF THE MACCABEES OF THE WORLD, OF SAME PLACE.

DESIGN FOR A BADGE.

SPECIFICATION forming part of Design No. 27,008, dated May 4, 1897.

Application filed November 16, 1896. Serial No. 612,371. Term of patent 14 years.

To all whom it may concern:

Be it known that I, BINA M. WEST, a citizen of the United States, residing at Port Huron, in the county of St. Clair and State of Michigan, have invented and produced a new and original Design for Badges, of which the following is a specification, reference being had to the accompanying drawing.

This invention relates to a design for a badge, and the badge is formed of metal, having the outline contour and shape shown in the drawing and with the ornamentation and embellishment of the design embossed on the face thereof.

15 The drawing shows a front view of my design.

1 represents the body portion of my design for a badge, and this body portion is oblong in shape and is arranged with the end portions 20 2 thereof rounded in the form of scrollwork.

The body portion 1 is provided with a narrow border 3, filled in with a fine ornamental scrollwork, leaving a blank space 5 on the inside thereof.

25 Located at the center of the body portion 1, and at an angle of about thirty-five degrees

therewith, is arranged a crown 6, while the lower end of a cross 7 is passed through said crown and extends below the edge of the body portion 1, while the opposite or upper end of 30 said cross projects considerably above the upper edge of said body portion.

What I claim is—

The design for a badge herein shown and described, the same consisting of a body portion of oblong shape and having ornamental scroll-shaped ends and provided with a narrow ornamental border, a raised crown centrally located on said body portion and lying at an angle with the same, a raised cross lying 40 diagonally across said body portion and with its lower portion appearing to pass through said crown and projecting below said body portion and with the upper portion of the cross projecting beyond the upper edge of said 45 body portion, substantially as set forth.

In testimony whereof I affix my signature in the presence of two witnesses.

BINA M. WEST.

Witnesses:

DE VERE HALL,
G. P. THOMAS.
